COMBINED BILLFOLD, CARD CASE, COIN PURSE, AND KEY CASE

Henry R. Godfrey, Gardner, Mass.

Application April 9, 1949, Serial No. 1,880

Term of patent 14 years

(Cl. D87—3)

To all whom it may concern:

Be it known that I, Henry R. Godfrey, a citizen of the United States, residing at Gardner, in the county of Worcester and State of Massachusetts, have invented a new, original, and ornamental Design for a Combined Billfold, Cardcase, Coin Purse, and Key Case, of which the following is a specification, reference being had to the accompanying drawing, forming part thereof.

Fig. 1 is a plan view of the inside of a combined billfold, cardcase, coin purse, and key case embodying my new design;

Fig. 2 is a plan view of the outside thereof with a portion of the tab broken away for convenience of illustration; and

Fig. 3 is an edge view thereof.

I claim:

The ornamental design for a combined billfold, cardcase, coin purse, and key case, as shown.

HENRY R. GODFREY.
